UNITED STATES PATENT OFFICE.

THURE A. JOHANSON, OF ST. CHARLES, ILLINOIS, ASSIGNOR TO THE CABLE COMPANY,
OF CHICAGO, ILLINOIS, A CORPORATION OF ILLINOIS.

PIANO SOUNDING-BOARD AND FRAME.

1,249,763.

Specification of Letters Patent. Patented Dec. 11, 1917.

Application filed March 20, 1914. Serial No. 825,944.

To all whom it may concern:

Be it known that I, THURE A. JOHANSON, a citizen of the United States, residing at St. Charles, in the county of Kane and State 5 of Illinois, have invented a certain new and useful Improvement in Piano Sounding Boards and Frames, of which the following is a full, clear, concise, and exact description, reference being had to the accompanying drawings, forming a part of this 10 specification.

My invention relates to a piano sounding board and frame.

Prominent objects of the invention are to 15 provide a simple and practical sounding board construction; to arrange to secure the proper crown or curvature of the same in a simple and effective manner, and to insure the maintenance of such crown or curvature 20 permanently; to insure against breakage or damage upon expansion or contraction of the sounding board; and to secure the foregoing and other desirable results in a simple and expeditious manner.

25 In the accompanying drawings, Figure 1 is a rear elevation of a piano having a sounding board embodying my present invention;

Fig. 2 is a vertical section taken on line 30 2—2 in Fig. 1;

Figs. 3 and 4 are views of details of construction.

In the drawings, I show a piano having a case 1 mounted on casters 2 in the usual 35 way. A sounding board 3 is located in the rear of the piano, the same consisting of a moderately thin web or sheet of material, preferably wood, as shown in Fig. 2. This sounding board has an irregular shape, as 40 shown in Fig. 1, having curved edges at the upper right hand and lower left hand portions of the board and substantially straight angularly-disposed intermediate portions connecting said curved edges. Ribs 3^a—3^a 45 are mounted upon the back face of the sounding board. As a preferred arrangement, edge or rim members 4 and 5 are secured to the rear of the sounding board along said curved edges. Other edge or 50 rim members 6, 7, 8 and 9 are preferably secured along the intermediate angularly disposed straight edges of the board, as shown in Fig. 1. The edge or rim members 4 and 5 are preferably made of laminated

strips of wood, although they could be of other material.

I also preferably provide, in accordance with my invention, a pair of spring members 10 and 11 which are preferably curved or bow-shaped, as shown in Fig. 1, and arranged with their convex sides toward and in contact with the curved edge or rim members 4 and 5. These members 10 and 11 are preferably made of laminated wooden strips also, bent in the proper form. They are 60 desirably arranged in position by having their ends fitted into apertures in the side uprights and top and bottom of the piano frame and then held in place by wedges 65 12—12 driven into such apertures and jammed against the end parts of said members. This sets the members 10 and 11 firmly in position and holds them in such 70 position permanently, it being understood that members 10 and 11 are adjusted, when 75 they are fitted in place, to such tension as to cause the sounding board to properly resist the flattening pressure of the strings and also to have the desired crown or curvature. Said members 10 and 11, by being securely 80 held in position, thus insure the sounding board retaining its proper position, resistance and resiliency. The resiliency of the members 10 and 11 has the advantage of 85 permitting a certain amount of movement on the part of the sounding board, such for example as a moderate amount of expansion 90 due to changes in temperature or moisture conditions, without causing any breakage or damage or any trouble. This moderate 95 amount of yield is a very desirable feature and the whole construction and arrangement is advantageous because it insures giving and maintaining the proper amount of curvature to the sounding board, and at the same time arranging to take up moderate changes in size of the sounding board due 100 to atmospheric changes.

It will be understood that changes and modifications may be made without departing from the spirit of the invention.

What I claim is:

1. The combination of a sounding board and resilient members located at opposite side edges of said board and arranged to 105 control the flexure thereof.
2. The combination with a sounding board, of a bow-shaped resilient member

acting inwardly against the edge of said sounding board and in substantially the plane thereof, and acting to effect the proper flexure of said board.

5 3. The combination with a sounding board, of a resilient member acting against the edge of said sounding board, in substantially the plane thereof, to control the flexure of said board.

10 4. The combination of a sounding board provided with a transversely-projecting edge member, and a bow-shaped spring member, of substantially the width of said edge member, acting upon the latter in substantially the plane of the sounding board.

15 5. The combination, in an upright piano, of a sounding board, and spring members located at diagonally-opposite corners of said piano and acting upon the edge of said sounding board to control the flexure thereof.

20 6. The combination, in an upright piano, of a sounding board, and spring members located at diagonally-opposite corners of said piano and acting upon the edge of said sounding board to control the flexure thereof, said spring members consisting of bow-shaped wooden strips.

25 7. The combination of a sounding board having oppositely disposed curved edges provided with transversely projecting curved edge members, and bow-shaped spring members acting upon said curved edge members.

30 8. The combination of a sounding board having oppositely disposed curved edges provided with transversely projecting curved edge members, and bow-shaped spring members acting upon said curved edge members, said spring members being secured to supporting members of the piano frame.

35 9. The combination, in an upright piano, of a sounding board having oppositely dis-

posed curved edge portions provided with correspondingly curved edge members, and also having angularly disposed straight edge portions between said curved edge portions, said straight edge portions being also provided with edge members whereof a vertical edge member fits against a vertical side of the piano frame, and curved spring members arranged at diagonally-opposite corners of the piano and having their ends secured in horizontal and vertical members of said piano, the convex faces of said curved spring members being in contact with the faces of said curved edge members on said sounding board.

40 10. The combination of a sounding board having one of its side edges provided with a convex member formed of laminated wooden strips, and a bow-shaped resilient member formed of laminated wooden strips, said resilient member lying in substantially the plane of the sounding board and having its convex face in contact with the convex face of the edge member on said sounding board.

45 11. The combination of a sounding board having opposite side edges provided with convex laminated wooden strips, and a pair of bow-shaped resilient members located at said opposite side edges of said board, said members lying in substantially the plane of the board and having their convex faces in contact with the convex faces of said edge strips on said board.

50 In witness whereof, I hereunto subscribe my name this 25th day of February, A. D., 1914.

THURE A. JOHANSON.
